(57) **CLAIM**

The ornamental design for a basket, as shown and described.

DESCRIPTION

FIG. 1 is a front elevation view of a basket, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a front and top perspective view thereof.

The broken lines in the figures illustrate portions of the basket that form no part of the claimed design. The eyes, nose and mouth on the basket represent surface indicia and not dimensional surface shading. The remaining surface shading depicts dimensional puckering along the seams and roundness of the lid and basket surface.
